[57] CLAIM

The ornamental design for a stock car hat, as shown and described.

DESCRIPTION

FIG. 1 is a top plan view of a stock car hat showing my new design;

FIG. 2 is a bottom plan view thereof;

FIG. 3 is a front end elevational view thereof;

FIG. 4 is an opposite end elevational view thereof;

FIG. 5 is a left side elevational view thereof, the right side is a mirror image; and,

FIG. 6 is a front perspective view thereof, the broken line showing of the human form is for illustrative purposes only and forms no part of the claimed design.
